UNITED STATES PATENT OFFICE.

JOSEPH TRISKA, OF OMAHA, NEBRASKA.

SPARK-PLUG.

1,138,811.

Specification of Letters Patent. Patented May 11, 1915.

Application filed January 6, 1914. Serial No. 810,582.

To all whom it may concern:

Be it known that I, JOSEPH TRISKA, a citizen of the United States, residing at Omaha, in the county of Douglas and State of Nebraska, have invented certain new and useful Improvements in Spark-Plugs, of which the following is a specification.

This invention relates to improvements in spark plugs, and has for its object to provide means for preventing the formation of a short circuit between the electrically energized conductor and the metallic housing or ground electrode of the spark plug.

In the use of spark plugs, as is well known, carbon will be deposited in the chamber of the spark plug, this being occasioned by the burning of the gas. From continued use of the spark plug a deposit of the carbon will usually be formed between the insulating plug and the metallic housing, with the result that the deposit will operate as a conductor or short circuit for the electric charges.

The frequent removals of spark plugs from engine cylinders required for the purpose of removing the carbon deposits therefrom, is a matter of inconvenience and expense. By use of the herein described construction, the carbon deposits will not form on the insulating plug, and it has been found to be useful for preventing the formation of carbon deposits within the air chamber.

The invention consists of the novel construction, combination and arrangement of parts as described herein and claimed, and as illustrated in the drawing, wherein,—

Figure 1 is a view in longitudinal section of a spark plug, and parts supporting the same, to clearly show relative position of parts. Fig. 2 is an end view of a scouring-member, rider or sleeve for the stem of the insulating plug, said stem being in transverse section. Fig. 3 is a side or plan view of the sleeve. Fig. 4 is a view, partly broken and in section, of the spark plug.

Referring now to the drawing for a more particular description, numeral 1 indicates a suitable support, as the wall of an engine cylinder, within which charges of gas may be delivered, to be ignited or exploded by means of the spark plug, and it will be understood that an ignition of gas occurs by

reason of the spark, said spark being occasioned by an electric charge passing from the finger *a* of the conductor 2 through the air-gap to the metallic finger 3, mounted upon the housing 4, said housing and the metallic parts connected therewith operating as the ground electrode. 60

Carbon will be deposited on the stem *b* of the insulating plug 5 within chamber 6 of the housing 4 from ordinary use of the spark plug, and normally will adhere thereto; and when, from continued use of the spark plug, the deposits have increased sufficiently to make contact with the metallic wall of member 4, the carbon will generally operate as a conductor between this member and the finger *a*, so that the charges of gas 70 will not be ignited.

I provide any suitable rider, scouring-member or sleeve 7, preferably formed with an annular ridge *c* between its ends, and mount it on the stem *b* of the insulating plug 5. At 8 is indicated a washer having a diameter of sufficient extent to prevent removal of the sleeve from said stem, the washer being disposed between the boss *d* of the conductor 2 and the terminal of 80 stem *b*.

In operation, the rider or sleeve will have sliding movements on the stem *b* by and on account of the vibrations caused by the explosions of ignited gas within the engine, or 85 on account of suction. Its sliding movements will be automatic, and will prevent the accumulation of carbon on said stem and will prevent the formation of deposits of carbon within the chamber of sufficient extent to cause the objectionable short circuit 90 mentioned.

At 9 is indicated a spring adapted to engage the sleeve or rider, for resisting its movements in one direction. On account of 95 suction and the explosions referred to, the sleeve will be reciprocated longitudinally on the stem *b*, the ridge *c* facilitating its movements.

Having fully described the several parts, 100 a further explanation relating to operation is not necessary.

What I claim and desire to secure by Letters Patent is,—

A spark plug, comprising, in combination 105 with a metallic housing having a cylindrical

chamber, an insulating plug having a body portion mounted in said housing and having a stem disposed centrally of the chamber for circumscribing a conductor, a detent member mounted on the terminal of the stem, a sleeve formed with an annular ridge and loosely mounted on said stem adjacent to said detent member, and a spring abut-

ting upon the body portion of the insulating plug for engagement with said sleeve. 10

In testimony whereof I have affixed my signature in presence of two witnesses.

JOSEPH TRISKA.
